PATRICK KENNEDY, OF BROOKLYN, NEW YORK, AND JOSEPH A. MISLAND, OF RAYONNE, NEW JERSEY, ASSIGNORS TO CONSOLIDATED RAILWAY ELECTRIC LIGHTING AND EQUIPMENT COMPANY, OF NEW YORK, N. Y., A CORPORATION OF MAINE.

DEVICE FOR SECURING ARMATURE-COILS.

1,124,456.

Specification of Letters Patent.

Patented Jan. 12, 1915.

Application filed February 8, 1911. Serial No. 607,337.

To all whom it may concern:

Be it known that we, PATRICK KENNEDY, a citizen of the United States, whose residence and post-office address is 177 Putnam 5 avenue, Brooklyn, New York, and JOSEPH A. MISLAND, a citizen of the United States, whose residence and post-office address is 97 West Thirty-third street, Bayonne, New Jersey, have invented certain new and useful Improvements in Devices for Securing 10 Armature-Coils; and we do hereby declare the following to be a full, clear, and exact description of the invention, such as will enable others skilled in the art to which it 15 appertains to make and use the same.

The invention relates to an improvement in devices for securing armature coils in dynamo electric machines to prevent any movement of the coils relative to the armature core, and more particularly at their 20 ends where the coils project outside the core slots.

It has been found in practice that as a result of continued vibration and magnetic 25 effects, the armature coils gradually work loose and bend out of place until they project outside the periphery of the armature core and strike the pole pieces of the field magnets, or rub through their insulation at 30 places of contact. In order to avoid such occurrence, it has heretofore been customary to secure the armature coils by a circular wrapping of wire, the ends of which were soldered together. However, if one of the 35 strands of such a wrapping breaks, or if the solder is melted by excessive heat developed in the armature from any cause, the loosened strand is free to fly out tangentially and create short circuits and mechanical 40 troubles which may well destroy the machine. Furthermore the breaking of a single strand is very likely to result in the complete tearing off of the entire wrapping, and the consequent loosening of the armature coils.

45 These conditions are more likely to occur in the case of machines which are connected to the axles of railway cars for the purpose of train lighting or in analogous cases, as the dynamo is then subjected to excessive vibration, shock and speed variation and furthermore must be inclosed to protect it from dirt and water and must be mounted in a comparatively inaccessible place. Thorough 50 inspection of the dynamo is very infrequent

and any loosening of the armature coils or 55 bands or any chaffing of insulation is likely to progress until electrical difficulties develop and interrupt the service. In accordance with my present invention these difficulties are obviated by mechanically holding the ends of the armature coils in fixed 60 position by means of a circular wrapping of wire held together by specially formed clamps at regular intervals around the circumference of the band or wrapping. 65

In the accompanying drawings forming a part of the specification, Figure 1 is a longitudinal view of the armature, partly in section; Fig. 2 is a perspective view of the band wire clamp, being partly broken away 70 so as to show the ends of the binding wire twisted around the clamp studs; Fig. 3 is a front elevation of the clamp with the band wire in section; Fig. 4 is an end view of the armature, showing in further detail the arrangement of the binding wire clamps and the slot wedges relative to the armature coils; Fig. 5 is a plan view of the band wire clamp showing one stud compressed and the other not compressed; Fig. 6 is a sectional elevation of the band wire clamp corresponding to Fig. 5. 75

Referring more particularly to the parts, 1 is the armature core, 4 the commutator, 5 the armature coils, 6 the slot wedges, and 7 the binding wire. A shell 9 supports the ends of the armature coils and also holds the armature core laminations in place through the aid of the bolts 10 and the ring 11 screwed on the shaft 2. In accordance 80 with United States Letters Patent No. 980,286 granted to us on January 3, 1911, a metal-wedge 6 is inserted in a dove-tail recess in the armature core teeth and then securely locked therein by enlarging the openings in the wedge from an elongated shape to one of circular form. In this way the coils are prevented from any radial movement and the wedges are prevented from longitudinal movement. 95

In addition to securing the armature coils in the core slots, it has been found expedient to further secure the coils where they project beyond the ends of the core. In accordance with our present invention this is accomplished by winding around the projecting coils a number of turns of binding wire, 7, which prevents them from spreading and 100

105

from any radial movement, and then permanently fastening the binding wires together by metal clamps 8, spaced regularly around the circumference. The clamp 8 is made of 5 any suitable metal, such as brass, and preferably consists of two bars 12 and 13, each having a hole near either end. The bar 13, on which sets the turns of binding wire, carries a hollow stud or rivet 14, projecting 10 upwardly from each hole. The studs may be fastened to the bar by compression, by upsetting their ends, by solder, or by any other suitable means, or may be integral therewith. After the band wires completely 15 fill the space between the studs, the other bar is set in place so that the studs extend through its openings, as shown on the right hand side of Fig. 6. The top bar is then forced down on the band wires by upsetting 20 the heads of the rivets or the ends of the studs, as shown on the left hand side of Fig. 6. Fig. 3 shows the finished clamp. Instead of wires, a plurality turns of a band of metal may be used for the purpose.

25 The clamps 8 have the effect to section-
alize the wrapping and confine the destruc-
tive effect of a broken strand to a wholly
unimportant fractional weakening of the
wrapping between the two adjacent clamps;

30 preventing the injury which ordinarily
arises from the flying out of the broken
strand, and rendering unnecessary the use of
solder which easily melts. Any material
circumferential movement of the band is ar-
rested by interference between the clamps
35 and the armature coils, while longitudinal
movement of the band is prevented by de-

pression of the armature coils at the place
where the band is wound around. The ends
of the binding wire are twisted around the 40
studs of the clamp, as shown in Fig. 2.

What we claim and desire to secure by
Letters Patent of the United States is:

1. A coil-binding means for armatures of
dynamo-electric machines, comprising a cir-
cumferential wrapping of wire in a number
of strands around the armature coils, a plu-
rality of underlying clamp bars over which
the wrapping is wound, and coöperating
clamp bars overlying the said strands and
secured to the underlying bars and restraining
the strands from relative circumferential
movement, substantially as described. 45

2. A coil-binding means for armatures of
dynamo-electric machines, comprising a cir-
cumferential wrapping of wire in a number
of strands around the armature coils, a plu-
rality of underlying clamp bars positioned
between adjacent coils and over which the
wrapping is wound and coöperating clamp
bars overlying the said strands and riveted
to the underlying bars to restrain the
strands from relative circumferential move-
ment, the ends of the wrapping wire being
secured to the rivets, substantially as de- 55
scribed. 60

In testimony whereof we affix our signa-
tures, in presence of two witnesses.

PATRICK KENNEDY.
JOSEPH A. MISLAND.
